CLAIM

The ornamental design for a collection of scent-infused wound sheets, as shown and described.

DESCRIPTION

FIG. 1 is a front perspective view of a first embodiment of a collection of scent-infused wound sheets in a vase.

FIG. 2 is a front elevation view of the collection of scent-infused wound sheets in the vase of FIG. 1.

FIG. 3 is a rear elevation view of the collection of scent-infused wound sheets in the vase of FIG. 1.

FIG. 4 is a right side elevation view of the collection of scent-infused wound sheets in the vase of FIG. 1.

FIG. 5 is a left side elevation view of the collection of scent-infused wound sheets in the vase of FIG. 1.

FIG. 6 is a top plan view of the collection of scent-infused wound sheets in the vase of FIG. 1.

FIG. 7 is a bottom plan view of the collection of scent-infused wound sheets in the vase of FIG. 1.

FIG. 8 is a front perspective view of a second embodiment of a collection of scent-infused wound sheets in a heated container.

FIG. 9 is a front elevation view of the collection of scent-infused wound sheets in the heated container of FIG. 8.

FIG. 10 is a rear elevation view of the collection of scent-infused wound sheets in the heated container of FIG. 8.

FIG. 11 is a right side elevation view of the collection of scent-infused wound sheets in the heated container of FIG. 8.

FIG. 12 is a left side elevation view of the collection of scent-infused wound sheets in the heated container of FIG. 8.

FIG. 13 is a top plan view of the collection of scent-infused wound sheets in the heated container of FIG. 8; and,

FIG. 14 is a bottom plan view of the collection of scent-infused wound sheets in the heated container of FIG. 8.

In the drawings, details shown in broken lines show unclaimed subject matter only and form no part of the claimed design.
